GOVERNOR TEST UNIT

Stanley E. Franklin, Wilmington, Calif., assignor to Marine Pumps, Inc., Wilmington, Calif., a corporation of California

Filed July 3, 1957, Ser. No. 46,820

Term of patent 14 years

(Cl. D26—1)

Des. 187,985

Fig. 3.

Fig. 1 is a perspective view of a governor test unit embodying the design;

Fig. 2 is a perspective view thereof from the side opposite Fig. 1; and

Fig. 3 is a side elevational view, to an enlarged scale, the opposite side having substantially the same appearance.

I claim:

The ornamental design for a governor test unit, substantially as shown and described.
